FILTER

Walter V. Kennedy, Central Falls, R. I., assignor
to Fram Corporation, a corporation of Rhode
Island

Application February 8, 1947, Serial No. 727,353

1 Claim. (Cl. 210—131)

1

This invention relates to a filter of the type particularly adapted for use with an internal combustion engine for filtering the lubricating oil thereof while the engine is in operation, although it may have various other uses.

Filters of this general type usually comprise a case which is permanently secured to the machine or some adjacent part with the liquid to be filtered leading to and from the casing for the flow of the liquid to be filtered. Within the casing there is located a cartridge which contains the filtering medium through which the liquid passes for the removal of the contaminant therein and when the cartridge accumulates contaminant up to the extent of its capacity then this cartridge is removed and a fresh cartridge put in its place. There is usually provided a cover for the casing which is removed in order that the cartridge may be taken from the casing for the substitution of a fresh cartridge. Some means such as a bolt is usually utilized for holding this cover in position.

The removal of the cartridge from the casing is somewhat of a messy operation where oil is filtered, in that the oil will cling to the cartridge upon removal and will drip on adjacent parts of the engine or get on the hands of the operator when the removal is made. Further, it is necessary for a wrench to be used to remove the nut which holds the cover in place and again necessary to use the wrench for tightening the bolt which holds the cover in place when the cover is replaced.

One of the objects of this invention is to provide an arrangement for the replacement of a used filtering medium without the need of use of a wrench.

Another object of this invention is to provide a means for quickly removing one cartridge and replacing it with another cartridge.

Another object of this invention is to provide for the replacement of a filter cartridge in which there will be no need of contact of the hands or tools or other parts with the oily surface of the cartridge, whereby the hands may become dirty or soiled.

Another object of the invention is to provide an arrangement for removing a used cartridge and replacing it with a fresh cartridge in which the possibility of dripping of the liquid filtered from the cartridge removed is reduced to a minimum.

With these and other objects in view, the invention consists of certain novel features of construction, as will be more fully described and particularly pointed out in the appended claim.

In the accompanying drawings:

Fig. 1 is a sectional view illustrating the filter;
Fig. 2 is a top plain view of the structure shown in Fig. 1;

Fig. 3 is a sectional view on line 3—3 of Fig. 2;
Fig. 4 is a sectional view on substantially line

4—4 of Fig. 2; and

Fig. 5 is a fragmental sectional view on line 5—5 of Fig. 1.

2

In proceeding with this invention, I provide a stud or boss which is permanently mounted on some part of the machine in connection with which the filter is used, and has leading to it the inflow conduit with the discharge conduit leading therefrom. A suitable cuplike frame is secured on this boss, which in turn has a bracket for mounting it in position. This framework serves largely the function of providing a detachable connection for a detachable member which contains the cartridge. This detachable member is in the form of a casing or shell which is recessed to receive the stud and is arranged to seal therewith. The center discharge conduit of the detachable member is arranged to seal with one of the conduits in the stud while the other conduit is so arranged that liquid to be filtered may flow into the shell of the detachable member. A filter medium is arranged between this inflow conduit and the discharge conduit for the passage of the liquid therethrough. Some sort of quick detachable connection is provided between this shell or detachable member and the permanent member whereby by telescoping the recess and stud and then turning the entire detachable member or shell a lock is provided which holds the two parts in assembled relation.

With reference to the drawings, a cup 10 is drawn from sheet stock which has a band 11 embracing the outer surface of the cup and is provided with outwardly extending portions 12 with flanges 13 to provide for mounting the bracket on some suitable surface support. A bolt 14 passes through the portions 12 having a head 15 at one end and a nut 16 on the threaded portion 17 at the other end for contracting the band so as to frictionally bind and hold the cup 10.

A solid cylindrical block or stud 20 is secured through the bottom 21 of the cup and held in this position by any suitable means such as welding as at 22. This stud is provided with a recess 23 in which a doughnut-shaped soft packing 24 of some synthetic rubber-like material is provided, it having a characteristic so that it will not be affected by the liquid which is to be filtered. A conduit 25 extends through this stud 20 and is provided with an attaching recess 26 for a copper tube or the

like. This conduit is usually used for the inflow of liquid to the filter. A conduit 27 is provided centrally of the stud and is in communication with the threaded recess 28 for the attachment of the discharge copper tube from the device. At the upper end of this discharge conduit 27 a nipple 29 is provided with a conical surface 30 for the purpose hereinafter mentioned.

A detachable member is designated generally 31 and consists of a shell 32 of metal which is rounded at its lower end as at 33 and recessed as at 34 of a size to receive the upper end of the stud 20. The walls of this recess when positioned over the stud will engage the soft packing 24 and provide a fluid tight seal at this location. The walls of the recess are turned inwardly as at 35 but are of a size to leave a clear opening about the member 29 for the flow of liquid inwardly into the shell 32 through the conduit 25.

A center tube 36 which is perforated throughout its extent is located in the shell 32 and has secured at its end 37 a flexible plate or diaphragm 38 which is located on this tube by reason of the projection 39 extending into it. A filtering medium consisting of cotton waste 40 is located about the center tube 36 and a second end plate or diaphragm 41 having an opening to receive the tube with flanges 42 surrounding the tube is positioned over the tube and rests against the waste at the other end. A corrugated sheet of perforated cardboard 43 embraces the waste pack and extends beyond the flexible plates 38 and 41. This plate 38 may be flexed downwardly by pressure of the inclined inner surface 44 of the shell 32 against the cardboard which in turn presses on the plate 38, while the plate 41 through the cardboard presses against the inwardly curved wall 33 of this shell. The center tube is free to be forced upwardly by reason of the spring of the plate 38 which acts as a diaphragm. The tube 36 is of a diameter to rest against the conical surface 30 of the member 29 and if the shell is forced downwardly there is a resilient urge on this tube through the diaphragm plate 38, tending to force the tube downwardly.

In order to detachably connect the shell 32 to the cup 10, this cup has inwardly extending lips 45 at four locations about its periphery which extend inwardly a substantial distance leaving a space sufficient to permit passage of the shell 32 into the cup. The ends of these lips are raised at one end as at 46 so as to provide camming ends or an inclined guiding surface beneath these lips and are turned down at their other end as at 46' to provide a stop. The shell 32 is provided with outward projections 47 of an extent substantially the extent of the lips and of a length which will pass between the ends of the lips in the circumferential extent. These projections extend outwardly a distance so that in one position of rotation the shell may be passed into the cup 10 and then upon turning, these projections 47 will extend beneath the lips 45, being guided into position by the upturned ends 46 of the lips so as to lock the shell member and base member or cup in assembled relation. In forcing the shell member downwardly so as to position the projections beneath the lips, a certain spring action occurs through the plate 38

so as to apply a resilient pressure upon the center tube and provide a good seal for the end of the center tube on the conical surface 30.

A locking finger 48 (see Fig. 4) consisting of a resilient strip 49 welded to the lip 45 as at 51 will engage the edge of a projection 47 and prevent turning of the shell to release position until the finger is manually lifted by handle 52 to permit this rotation.

Liquid will flow in through the conduit 25 and surround the filter material 40 passing through the filter material then into the center tube 36 and downwardly out through the discharge conduit 27. After the filter element collects all the contaminant that it can hold the entire shell 31 may be removed by turning the shell so that the projections 47 move out from under the lips 45 and then this shell may be withdrawn from the cup 10 and thrown away, while a new shell 31 may be used to replace it. Thus the parts with which the liquid to be filtered contacts are not touched by the hand nor is it necessary to utilize any wrench in the removal or replacement of the cartridge.

I claim:

A filter comprising fixed and removable members the fixed member having a projection with a cylindrical surface with an inlet conduit and a discharge conduit extending axially therethrough, a nipple at the axis of said cylindrical projection through which one of said conduits passes, the removable member having a recess to telescopingly receive said projection, an elastically compressible gasket to provide a liquid seal between the wall of said projection and the wall of said recess in which it is telescoped when the projection is in said recess, said removable member provided with a filter cartridge having a conduit to register with and provide a sealing seat with said nipple when the members are assembled to separate the flow through the registering conduit from the other conduit, means communicating the other conduit of said projection through the recessed telescoping portion of said removable member, and interlocking means rigid with each of said members to detachably hold said members in assembled relation by a relative movement of said members a fraction of a revolution, said means providing a camming of said members toward each other to draw the engaging conduits into sealing relation.
